UNITED STATES PATENT OFFICE.

EDWARD L. MCCLAIN, GREENFIELD, OHIO.

DESIGN FOR A BACK-BAND HOOK.

SPECIFICATION forming part of Design No. 33,470, dated October 30, 1900.

Application filed July 2, 1900. Serial No. 22,370. Term of patent 3½ years.

To all whom it may concern:

Be it known that I, EDWARD L. MCCLAIN, a citizen of the United States of America, and a resident of Greenfield, in the county of Highland and State of Ohio, have invented a certain new and original Design for a Back-Band Hook, of which the following is a specification.

Figure 1 is a front elevation of a back-band hook embodying my invention. Fig. 2 is a central vertical sectional view of the same.

The principal feature of my design is a plate having formed integral therewith a series of hooks arranged one above the other.

Plate A has a series of three quadrilateral perforations situated one above the other,

upon the lower edges of which are formed three upwardly-projecting and inwardly-curved hooks a , a' , and a'' , whose inner edges terminate at the plane of the rear face of plate A. Plate A has likewise two upper laterally-projecting perforated lugs a^3 and a^4 and two lower laterally-projecting lugs a^5 and a^6 . 20

What I claim is—

The design for a back-band hook as herein shown and described.

EDWARD L. MCCLAIN.
